Patented Oct. 5, 1915.

UNITED STATES PATENT OFFICE.

SALVATORE GUADAGNINO, OF NEW YORK, N. Y.

VENDING-MACHINE.

1,155,918.

Specification of Letters Patent.

Patented Oct. 5, 1915.

Application filed October 26, 1914. Serial No. 868,711.

To all whom it may concern:

Be it known that I, SALVATORE GUADAGNINO, a subject of the King of Italy, and a resident of the city of New York, borough of Brooklyn, in the county of Kings and State of New York, have invented a new and Improved Vending-Machine, of which the following is a full, clear, and exact description.

This invention relates to improvements in vending machines, and has for an object to provide an improved construction of a minimum number of parts which are simple and strong, and which will not readily get out of order.

Another object of the invention is to provide an improved construction which will properly vend an article, the same being associated with a coin controlling construction which will operate only with a certain sized coin but will not become clogged or stopped up by insertion of coins, washers or similar devices.

In the accompanying drawings—Figure 1 is a longitudinal vertical section through a vending machine embodying the invention, part of the same being broken away; Fig. 2 is a top plan view of the vending and coin controlled structure; Fig. 3 is a section through Fig. 2 on line 3—3; Fig. 4 is a view similar to Fig. 2, certain parts having been removed; Fig. 5 is a section through Fig. 4 on line 5—5.

Referring to the accompanying drawings by numerals, 1 indicates a suitable casing of any desired kind provided with a chute 2 for carrying candy, gum, or other articles 3. These articles are designed to engage the inner end of the push rod 4 and be moved from the chute 2 as shown in dotted lines in Fig. 1. When a coin of the proper size is inserted into the machine plunger 4 may be moved to the rear once and then pulled back automatically. A second movement will be prevented unless another coin has been inserted. The plunger 4 is provided with a pin 5 and a spring 6 which acts against pin 5 and against a stop 7 so as to normally hold the plunger in an outer position as shown in Figs. 1 and 2. The plunger 4 is mounted in a face plate 8 and the upstanding stop 7 of plate 9. The inner end of plunger 4 is flattened out and receives a plate 10 having a depending portion 11 projecting through a suitable aperture in the flattened portion 12 of the plunger 4 so that the depending portion 11 may extend into an aperture 13 of a sliding plate 14.

The sliding plate 14 (Fig. 4) bears at one edge against the guiding bar 15 and has connected therewith near the opposite edge a pivotally mounted member or plate 16, the connection being made by a suitable pivotal pin 17.

The plate 18 is provided with an upwardly extending tongue 18. Plate 14 is provided with notches 19 and 20 with a rounded projection 22 arranged therebetween. The extreme front of plate 14 is provided with a beveled edge 23 designed to engage and raise the pin 24 (Fig. 5) when the plate is moving back to its normal position as shown in Fig. 4. The pivotally mounted plate 16 is provided with a notch 19' and also a notch 20' together with a projecting portion 22'.

In operation a coin of the proper size may be fitted in notches 20 and 20' so as to hold the plate 16 in such a position that the spur or pawl shaped member 25 will remain out of engagement with any of the teeth 26 on the guiding bar 27 as the plunger 4 is moved to the rear. When the plunger has been moved to almost its extreme rear position the tongue 18 dislodges the coin from between the jaws formed by plates 14 and 16, whereby the coin may be dropped into the box 28. The aperture 13 in plate 14 is arranged above a slot 29, which slot accommodates the lower portion of the extension 11 so as to guide the same in the reciprocatory movement of the plunger 4. A spring 30 is arranged between the plate 16 and bar 27 so as to normally press the bar 25 into teeth 26 and thereby lock the plate 14 against movement.

It will be noted that the spring 30 is made substantially U-shaped whereby long side edges are presented which will continue to engage the plate 16 even though the same may be moved to the rear an appreciable distance. It will be noted that between the plate 16 and plate 14 is a space 31 which accommodates the stop 32 secured to the base plate 33. If, for instance, a coin larger than the coin designed to be used is forced into the notches 20 and 20' the plate 16 will be moved pivotally until the corner 34 of plate 16 will strike against pin 32 in case the plunger is moved toward the rear. A movement of this character will not be sufficient for dislodging one of the packages 3 from

chute 2 so that a larger coin will not operate the device. However, the extra large coin will be engaged by the tongue 18 and dislodged. If for any reason the extra large 5 coin should not be discharged the next succeeding coin of the proper size will dislodge the extra large coin and force the same into the receptacle 28.

The plate 9 is provided with an aperture 10 35 while plate 14 is provided with an aperture 36, these apertures being designed to receive the pins 24 and 37, respectively. The pins 24 and 37 are beveled in opposite directions so that the pin 37 has the bevel facing 15 the front plate 8 as shown in Fig. 1, while pin 24 has the bevel facing in the opposite direction so as to engage the beveled edge 23. Pin 37 is arranged centrally of the space between sockets 20 and 20' so as to fit into 20 the aperture of a washer and thereby prevent any engagement of the plunger. Also by reason of the aperture in the washer the pin 24 will not be raised but will remain in the aperture 35.

25 Pins 24 and 37 are rigidly secured to a spring plate 38 which is preferably provided with a bowed portion 39 so as to give a better resilient effect. Also a spring 40 is provided held in place by a suitable screw 41 for resiliently holding the end of plate 38 against plate 9. As shown in Figs. 1 and 3 the spring plate 38 is held at one end by a screw 42 firmly to plate 9. Screw 42 also acts as means for clamping plate 9, bar 27 30 and base 33 together though suitable rivets are preferably provided for rigidly securing bars 15 and 27 rigidly to base 33.

In operation after the parts have been assembled as shown in Fig. 1 a coin is inserted 40 as for instance a one cent piece, the same being forced through the slot 43. When the coin is forced through the slot 43 the same engages the forward ends of plates 14 and 16 and moves pivotal plate 16 from plate 14 45 so that the coin may pass into the notches 20 and 20'. The plunger 4 is then forced inwardly until the lowermost packet 3 has been forced off the chute 2, as shown in dotted lines in Fig. 1. The one cent piece is 50 of such a size as to hold the pawl 25 out of engagement with teeth 26, and also to hold the point 34 a sufficient distance from stop 32 for preventing a free passage. Upon the completion or near completion of the inward 55 movement of plunger 4 tongue 18 will engage the one cent piece and force the same out of contact with plates 14 and 16 so that the coin will drop into the receptacle 28. If a washer of the same size and thickness 60 as the one cent piece is forced into the sockets 20 and 20' no result will follow. The plunger cannot be forced inwardly after this has been done, but a one cent piece may be easily forced into position in the sockets 20 65 and 20', forcing the washer out of said sock-

ets and causing the same to fall into the receptacle 28. When this has been done the plunger may be moved to the rear as above set forth. By this construction and arrangement it will be observed that the device will not become out of order when a washer has been inserted but will merely refuse to operate until a coin of the correct size has been placed in position. When a coin, as for instance, a one cent piece is forced into sockets 20 and 20' the same raises pin 37 and holds the same raised. The raising of pin 37 of course raises the plate 38 and pin 24, whereby the sliding plate 14 is free to move. When a washer is in sockets 20 and 20' pin 37 is of course projecting into the hole in the washer so that pin 24 is still in engagement with the plate 9 as the same is still projecting into aperture 35. It will be evident that suitable apertures are provided in plate 9 for accommodating pins 24 and 37 as shown in Fig. 5. If a coin is inserted into the notches 20 and 20' which is smaller than is intended to be received by the device said coin will not injure the device in any way 90 nor will it work the same, but will be lost to the would be purchaser. For instance, if the device was arranged to utilize a one cent piece and then a ten cent piece was inserted the ten cent piece would be forced into the 95 receptacle 28 in a similar manner to the way a washer is forced into said receptacle.

Plate 14 is provided with a pin 44 which extends into a slot 45 formed in the base 33. This is to limit the reciprocatory movement 100 of the plate. As shown in Fig. 4, the end of the pivotally mounted member 16 which engages the coin as the coin passes through the front plate 8 is provided with a pointed end 46 which will prevent the use of lead slugs, 105 paper or pieces of wood as such matter will be entered by point 46 and will therefore not operate the machine.

What I claim is:—

1. In a device of the character described, 110 a casing, a plunger arranged to reciprocate in said casing so as to displace articles arranged in the casing, a base plate formed with a slot, a sliding plate, a pivotally mounted plate associated with said sliding 115 plate and movable therewith, a spring for normally pressing said pivotally mounted plate toward said sliding plate, said plates being formed with notches for receiving a coin therebetween, said coin holding said pivotally mounted member in a predetermined position, means adapted to engage said pivotally mounted member when not held in said predetermined position for preventing a sliding movement thereof, and 120 means connected with said plunger for moving said plates when said plunger is moved.

2. In a vending machine, means for vending an article, a projection extending from said means, a sliding plate for controlling 130

the movement of said projection and the vending means, said sliding plate having a coin receiving notch, a pivotally mounted plate arranged adjacent said sliding plate and pivotally connected therewith so as to be movable therewith, said pivotally mounted plate being provided with a coin receiving notch, means for guiding a coin into said notches whereby said pivotally mounted member is held in a predetermined position, a plurality of means arranged in the path of movement of the pivotally mounted plate when not in said predetermined position, and means for ejecting said coin after said sliding plate has been moved a predetermined distance.

3. In a device of the character described, a reciprocating member, a sliding plate, means for connecting said reciprocating member and said sliding plate, a pivotally mounted plate connected with said sliding plate and movable therewith, said plates having oppositely arranged portions for receiving a coin of a predetermined size, means associated with said sliding plate for locking the same against movement, said means being disengaged by a coin of a predetermined size arranged between said pivotally mounted plate and said sliding plate, and means for preventing said pivotally mounted plate from sliding until a coin of a predetermined size has been inserted between said pivotally mounted plate and said sliding plate.

4. In a device of the character described, a sliding member for vending an article, a projection connected with said sliding member, a sliding plate formed with an aperture for receiving said projection whereby whenever said sliding member is moved said sliding plate will be moved, a locking device for locking said sliding plate against movement, said locking device including a pair of spring pressed pins, said pins being connected so as to operate simultaneously, means for guiding a coin to a position against one of said pins whereby said last mentioned pin will be raised and the other pin will also be raised therewith for unlocking said sliding plate, a pivotally mounted plate adapted to bear against said coin, and means for preventing said pivotally mounted plate from sliding with said sliding plate until a proper sized coin has been placed beneath said coin operated pin.

5. In a vending machine of the character described, a reciprocating plunger, a sliding plate, means for connecting said plunger and said sliding plate, a pivotally mounted plate connected with said plunger and movable therewith, means for guiding a coin to a position between said pivotally mounted plate and said sliding plate so as to hold the pivotally mounted plate in a predetermined position when the coin is of the proper size,

a spring pressing against said pivotally mounted plate for urging the same in a predetermined direction, a stop arranged to engage said pivotally mounted plate when moved to one extreme, and a toothed member adapted to engage said pivotally mounted plate when moved to the opposite extreme position, whereby the pivotally mounted plate together with the sliding plate cannot move when a coin of an incorrect size is used.

6. In a device of the character described, the combination with an article holding device, of a reciprocating plunger for forcing an article from said article holding device each time the plunger moves inwardly, a spring for resiliently holding said plunger in an outer position, a sliding controlling plate, means extending from said plunger to said sliding controlling plate for locking said plate and said plunger together, said plate being formed with an aperture near one end, a pin extending into said aperture, a spring member supporting said pin, means for holding said spring member against lateral movement, a washer detecting pin extending from said pin member and arranged in the path of a coin, and means for guiding a coin to said last mentioned pin member, said coin being designed to raise said pin member and the spring connected therewith together with the first mentioned pin whereby said sliding plate is unlocked.

7. In a device of the character described, a reciprocating plunger, a sliding plate, means for connecting the plunger and plate so that one cannot move without the other, said sliding plate being formed with an aperture, a retaining plate rigidly secured in position above said sliding plate and provided with a pair of apertures, a flat spring secured to said retaining plate, the securing means being arranged adjacent one end of the flat spring so that the spring may freely move up and down, a pair of pins secured to said spring formed with beveled ends facing in opposite directions, one of said pins extending into said aperture in said plate and the other extending to one side of said plate in the path of movement of a coin, whereby when a washer is inserted the last mentioned pin will not be elevated but when a coin of the proper size is inserted said last mentioned pin will be elevated and consequently will elevate said spring and the other pin for unlocking said plate, and means for guiding a coin to a position below said elevated pin.

8. In a device of the character described, a reciprocating push rod, a reciprocating plate, means for connecting said plate and said push rod so that they must act together, a pivotally mounted member arranged adjacent said plate and rigidly connected with the plate, a spring for normally urging one end of said pivotally mounted member to

ward said plate, stops arranged adjacent one end of said pivotally mounted member, means formed on said pivotally mounted member for engaging said stops when there is no coin in the device or when there is a coin of an improper size so that the sliding plate and said plunger cannot be moved an appreciable extent, means for guiding a coin to a position between said pivotally mounted member and said plate, said coin if of the proper size acting to prevent said pivotally mounted member from engaging any of said stops, and means projecting to a position

adjacent said pivotally mounted member for extending into the aperture of a washer if a washer is inserted into the device in place of a coin whereby the device cannot be operated.

In testimony whereof I have signed my name to this specification in the presence of two subscribing witnesses.

SALVATORE GUADAGNINO.
